UNITED STATES PATENT OFFICE

2,679,804

FUEL INJECTION PUMP

Waldemar O. Bischoff, South Hadley Falls, Mass.,
assignor to American Bosch Corporation,
Springfield, Mass., a corporation of New York

Application February 11, 1953, Serial No. 336,329

7 Claims. (Cl. 103—2)

1

This invention relates to fuel injection apparatus and has particular reference to a new and improved apparatus of the distributor type which is relatively simple and compact in construction, yet efficient in operation.

An object of the invention is to provide a relatively simple and compact fuel injection apparatus adapted to supply fuel to a plurality of outlets successively.

Another object of the invention is to provide an apparatus of the type set forth which is of such size that it may be positioned in the space usually occupied by the ignition distributor and driven by the type of drive usually employed for driving the ignition distributor and thereby providing a simple, low cost drive and adaptability to the engine.

Another object is to provide a device of the type set forth which employs a relatively short fuel path between the pump and distributor and which allows the employment of a delivery valve with relief action.

Another object is to provide a new and improved fuel injection pump for an apparatus of the type set forth.

Another object is to provide a new and improved arrangement for automatically effecting oscillation of the distributor during the operation of the device and thereby increasing the useful life of the device.

Another object is to provide a device of the type set forth with means whereby the operative elements may be lubricated with lube oil.

Another object is to provide a device of the type set forth which employs a high pressure fuel metering arrangement.

Another object is to provide a new and improved drive arrangement for a device of the type set forth which reduces the power requirements of the device.

Another object is to provide a device of the type set forth which eliminates the necessity of an expensive supply pump.

Another object is to provide a new and improved device of the type set forth which is adapted for either flange mounting or base mounting without sacrificing the compactness or simplicity of the device.

Other objects and advantages of the invention will be apparent from the following description taken in connection with the accompanying drawings. It will be understood that changes may be made in the details of construction and arrangement of parts without departing from the spirit of the invention, as the preferred

forms have been given by way of illustration only. Referring to the drawings:

Fig. 1 is a side view of a form of the device employing an external governor;

Fig. 2 is an end view of the device shown in Fig. 1 from the drive end;

Fig. 3 is an end view of the device shown in Fig. 1 from the distributor end;

Fig. 4 is a longitudinal sectional view of the device shown in Fig. 1;

Fig. 5 is a sectional view taken on line 5—5 of Fig. 4, looking in the direction of the arrows;

Fig. 6 is a sectional view taken on line 6—6 of Fig. 4, looking in the direction of the arrows;

Fig. 7 is a fragmentary sectional view taken on line 7—7 of Fig. 4, looking in the direction of the arrows;

Fig. 8 is a sectional view of the double face cam drive member;

Fig. 9 is a fragmentary side view of the double face cam taken on an enlarged scale;

Fig. 10 is a top view of a form of the device employing an internal governor;

Fig. 11 is a longitudinal sectional view of the form of the device shown in Fig. 10; and

Fig. 12 is a sectional view taken on line 12—12 of Fig. 10, looking in the direction of the arrows.

Referring more particularly to the drawings wherein similar reference characters designate corresponding parts throughout, the device shown embodying the invention comprises a housing 10 in which is positioned the hydraulic head 11 by brazing or other suitable means at 12.

Within the hydraulic head 11 is positioned the distributor 13 which has the splined end 14 adapted to engage the splined end 15 on drive shaft 16 which is adapted to be connected to the engine and driven thereby.

On the periphery of distributor 13 is secured the double face cam 17 which is secured to distributor 13 by the screws 18, wedge keys 18a and retaining ring 18b or other suitable means whereby rotation of distributor 13 effects simultaneous rotation of double face cam 17. The arrangement shown for securing the double face cam 17 to the distributor 13 provides reasonably accurate location of the cam in relation to the distributor ports and eliminates all looseness or play between the distributor shaft and the cam. Due to the shape of the keys 18a and keyways 18c any tightening of screws 18 will cause cam 17 to move tightly against retaining ring 18b. Continued tightening of the screws 18 will force keys 18a to move in keyways 18c until they are wedged securely between cam

17 and distributor shaft 13 thereby eliminating all looseness between them.

Drive shaft 16 is positioned within adapter 19 and suitable seals such as the O rings 20 and carbon seal ring 20a are provided to prevent leakage.

Distributor 13 is provided with metering portion or extension 21 having the axial passage 22 having the radial spill ports 23 adapted to be controlled by metering sleeve 24 surrounding metering portion 21 and controlled by control shaft 25 which is connected to sleeve 24 by the eccentric pin or other suitable means 26. On shaft 25 is provided lever 27 which may be connected to the engine governor or other suitable controls for controlling the setting of metering sleeve 24.

Insert 28 may be secured to housing 10 by brazing or some other suitable means. This construction in effect provides a one piece head and housing for the pump. Distributor 13 is closely fitted to both head 11 and insert 28 providing a good rigid bearing support on both sides of cam 17 and also preventing the leakage of fuel from the head 11 and/or sump 63 into the cam compartment. Lubricating oil may be supplied to the cam compartment for the lubrication of the cam and rollers. If desired, the cam and rollers may be lubricated by fuel by providing a passage between the cam compartment and either sump 58 or sump 63.

Distributor 13 is provided with a bore in which is positioned pumping plunger 29 in which is positioned delivery valve 30 which is normally retained in closed position by delivery valve spring 31. The delivery valve can be provided with a relief piston in a manner well known to the art.

The pumping plunger 29 is provided with the reduced portion 32 through which extends a fuel passage 33. Pumping plunger 29 is adapted to be retained against cap 35 by means of coil spring 34.

Face cam 17 is of the double face type, as shown particularly in Figs. 8 and 9, and passes between rollers 36 on pins or pivots 37 and rotation of distributor 13 and metering portion extension 21 effects rotation of double face cam 17 which effects a continuous reciprocation of distributor 13 and metering portion 21 which serves to oscillate the distributor, thus evenly distributing the wear over its surface and at the same time effects pumping action of injection pump pumping plunger 29 into the chamber 38 from which the fuel, when the pressure in chamber 38 is sufficient, opens delivery valve 30 and allows fuel to pass into distributing chamber 39 from which fuel passes through openings 40 to port 41 through which fuel passes through slot 42 to each of the outlets 43 successively upon rotation of distributor 13 and from outlets 43, the fuel is supplied through lines, not shown, to each of the combustion chambers of the engine successively. The double face cam 17 controls the oscillation of the distributor in both the upward and downward directions thereby eliminating the need for return springs and reducing the driving power required because the spring forces are removed.

In the form of the invention shown in Figs. 10, 11 and 12, which is the form having the centrifugal internal governor, the governor is of the ball type having the balls 44 with the double cones 45. The governor force is resisted by torsion springs 46 and 47 working on levers 48 and

49 respectively which link directly to the fuel metering sleeve 24.

The pump housing 10 is extended to include the governor mechanism.

5 The cones 45 bear against the balls 44 which are driven by retainer cage 45a. The fuel load adjustment screw 49 is held in its desired position by elastic stop nut 50. Full load stop plate 51 is a part of governor lever 48 which pivots on throttle shaft 52 and bears on the floating cone. Torsion spring 46 on shaft 52 bears against lever 48 and resists the motion of the cone 45.

Metering sleeve 24 on distributor 13 is moved by lever 49a through pivot pins 53 fastened to lever 49a which pivots on idle adjustment shaft 54. Spring 47 bears against lever 49a. Shutoff lever 55 is fastened to shaft 56 and operates against lever 49a.

As the drive shaft 16 is rotated, the distributor 20 and metering portion 21 are simultaneously rotated as is the face cam 17, and the cam effects oscillation of the distributor 13 and metering portion 21.

Because the plunger 29 is held against plug 35 25 by the spring 34 or other suitable means this positive two direction oscillation of the distributor 13 by cam 17 causes a pumping action in chamber 38. Fuel enters the pump through inlet port 57 into sump 58. On the filling or suction stroke of distributor 13, ports 59 are open to slots 60 through annulus 61 and ports 62 into chamber 38. During this time the delivery valve 30 is held tightly against its seat by spring 31. thereby preventing any flow of fuel to or from 35 the outlet ports.

Near the end of the filling stroke, rotation of distributor 13 causes slots 60 to go out of communication with ports 59 and fuel flow through these ports is stopped. Meanwhile slot 42 has 40 become aligned with one of the discharge ports 43 and is ready for the injection of fuel and further rotation of the shaft 16 and cam 17 starts the compression or injection stroke.

With inlet ports 59 closed and valve 30 against 45 its seat, compression of the fuel will cause it to flow through axial passage 22 to ports 23 into sump 63 which is connected to filling sump 58 through vent line 64.

Metering sleeve 24 is set at a predetermined 50 position for the quantity of fuel desired per stroke and fuel will continue to flow out of ports 23 until the ports are closed by the sleeve due to oscillation of metering portion 21. With all 55 passages closed, further compression of the fuel will lift the delivery valve from its seat and fuel can now flow through the ports 41 to the selected outlet from which it will flow to the combustion chamber connected to the selected outlet.

60 When the pump is operating the governor balls 44, which are driven by the cage 45a, tend to move radially outward due to centrifugal force. The shape of the cone translates this radial motion to an axial movement of the floating cone and because both of the cones have the same profile, the net axial movement of the floating cone is doubled.

65 This axial motion is resisted by the force exerted by spring 46 working against lever 48 which bears on the floating cone. The amount of force developed by spring 46 can be varied within predetermined limits by the operator by turning throttle shaft 52. Rotation of the shaft 52 will increase or decrease the spring force by winding up or unwinding torsion spring 46.

Sleeve control lever 49a pivots on idle shaft 54. On this lever 49a are two pivot pins 53 which engage fuel metering sleeve 24. Spring 47 forces lever 49a to bear against lever 48. Any movement of the floating cone is transmitted to lever 48 and results in a relative movement of lever 49a and this motion of lever 49a causes sleeve 24 to move a proportionate amount.

The tension or load applied by torsion spring 47 can be varied by rotation of shaft 54. Should either spring 46 or 47 fail, the floating cone would immediately move the levers 48 and 49a and the fuel metering sleeve 24 to lower fuel delivery or shutoff position.

From the foregoing, it will be seen that I have provided simple, efficient and economical means for obtaining all of the objects and advantages of the invention.

I claim:

1. In a device of the character described, a housing, a member mounted for rotation in said housing, said member having a distributing portion and a metering portion, said member having a bore and a pumping member in said bore, said pumping member communicating with said metering portion and said distributing portion and means for effecting simultaneous rotation and reciprocation of said distributing portion and reciprocation of said pumping member in said bore, and a discharge valve in a bore in said pumping member.

2. In a device of the character described, a housing, a member mounted for rotation in said housing, said member having a distributing portion and a metering portion, said member having a bore and a pumping member in said bore, said pumping member communicating with said metering portion and said distributing portion and means for effecting simultaneous rotation and reciprocation of said distributing portion and reciprocation of said pumping member in said bore, said metering portion having a spill passage and means surrounding said portion for controlling the quantity of fuel spilled through said spill passage.

3. In a device of the character described, a housing having a bore, a member mounted for rotation and axial movement in said bore, said member having a distributing portion adjacent one end thereof and a metering portion adjacent the opposite end thereof, said member having a bore in the end thereof adjacent said distributing portion, a pumping member in said bore in said distributing portion and adapted to be reciprocated upon axial movement of said member and a plurality of outlets adapted to communicate successively with said distributing portion upon its rotation, said pumping member having a bore communicating with said distributing portion and the pumping portion of said pumping member and a check valve in said bore in said pumping member.

4. In a device of the character described, a housing having a bore, a member mounted for rotation and axial movement in said bore, said member having a distributing portion adjacent one end thereof and a metering portion adjacent the opposite end thereof, said member having a bore in the end thereof adjacent said distributing portion, a pumping member in said bore in said distributing portion and adapted to be recipro-

cated upon axial movement of said member and a plurality of outlets adapted to communicate successively with said distributing portion upon its rotation, and a face cam surrounding said member for effecting axial movement thereof upon the rotation of said member, said pumping member having a bore communicating with said distributing portion and the pumping portion of said pumping member and a check valve in said bore in said pumping member.

5. In a device of the character described, a housing having a bore, a member mounted for rotation and axial movement in said bore, said member having a distributing portion adjacent

15 member having a distributing portion adjacent one end thereof and a metering portion adjacent the opposite end thereof, said member having a bore in the end thereof adjacent said distributing portion, a pumping member in said bore in said

20 distributing portion and adapted to be reciprocated upon axial movement of said member and a plurality of outlets adapted to communicate successively with said distributing portion upon

its rotation, and a face cam surrounding said member for effecting axial movement thereof upon the rotation of said member, said metering portion having a spill passage and means for controlling the quantity of fuel spilled therethrough.

30 6. In a device of the character described, a housing having a bore, a member mounted for rotation and axial movement in said bore, said member having a distributing portion adjacent

35 one end thereof and a metering portion adjacent the opposite end thereof, said member having a bore in the end thereof adjacent said distributing portion, a pumping member in said bore in said distributing portion and adapted to be reciprocated upon axial movement of said member and a plurality of outlets adapted to communicate successively with said distributing portion 40 upon its rotation, and a check valve in the fuel path between said pumping member and said distributing portion, said metering portion having a spill passage and means for controlling the quantity of fuel spilled therethrough.

45 7. In a device of the character described, a housing having a bore, a member mounted for rotation and axial movement in said bore, said member having a distributing portion adjacent

50 one end thereof and a metering portion adjacent the opposite end thereof, said member having a bore in the end thereof adjacent said distributing portion, a pumping member in said bore in

55 said distributing portion and adapted to be reciprocated upon axial movement of said member and a plurality of outlets adapted to communicate successively with said distributing portion upon

its rotation, said pumping member having a bore communicating with said distributing portion and the pumping portion of said pumping member and a check valve in said bore in said pumping

member, said metering portion having a spill passage and means for controlling the quantity of fuel spilled therethrough.
